UNITED STATES PATENT OFFICE

91,975

DESIGN FOR AN ADVERTISING DEVICE OR SIMILAR ARTICLE

Raleigh W. Young, San Francisco, Calif.

Application December 8, 1933, Serial No. 49,989

Term of patent 14 years

all whom it may concern:

Be it known that I, RALEIGH W. YOUNG, a citizen of the United States of America, residing in the city and county of San Francisco, State of California, have invented a new, original, and ornamental Design for an Advertising Device or Similar Article, of which the following is a specification, reference being had to the accompanying drawing, forming part thereof:

Fig. 1 is a perspective view of an advertising device, or similar article; and

Fig. 2 is an end perspective view showing my new design.

The nature of my design, as fully represented in the drawing, comprises a rumpled sheet of sandpaper to represent the wind-blown ripples of a

sand desert, upon which is placed a pair of hingedly connected triangular sheets to represent a pyramid.

Also placed upon the sheet of sand paper and in front of the pyramid is a camel carrying a Beduin or other similar character leading a second camel laden with a package of the goods advertised by the ornamental display.

At the rear edge of the sheet of sand paper and back of the pyramid is a back-drop, in front of which is a pacing caravan of laden camels.

I claim:

The ornamental design for an advertising device or similar article, as shown and described.

RALEIGH W. YOUNG.
